UNITED STATES PATENT OFFICE.

WESLEY H. BENNINGTON, OF CLEVELAND, OHIO.

PHONOGRAPH-CABINET.

1,327,977.

Specification of Letters Patent. Patented Jan. 13, 1920.

Application filed January 13, 1919. Serial No. 270,805.

To all whom it may concern:

Be it known that I, WESLEY H. BENNINGTON, a citizen of the United States, residing at Cleveland, in the county of Cuyahoga and State of Ohio, have invented certain new and useful Improvements in Phonograph-Cabinets, of which the following is a specification.

This invention relates to the construction of cabinets adapted to the various types of phonographs. Upright structures of this class are generally made more or less ornamental and provided with a lower receptacle for the storage of records, the phonograph being mounted in a compartment above said receptacle and the structure being surmounted with a hinged cover, which is swung upward on its hinges to admit of access to the machine for changing of records and for regulating the tone of the instrument.

The object of the present invention is to produce a structure that is more convenient and commodious than the cabinets as heretofore constructed, and with this object in view, I provide a stationary top which furnishes a suitable location for a clock, a lamp, statuary, bric-a-brac, or for a curio case, as the top member is not disturbed in regulating the instrument, access being had to the phonograph compartment through a novel sliding door construction arranged in the vertical front of the cabinet. The invention further provides a novel, convenient, temporary receptacle or support for records, to be utilized while making changes of records on the instrument.

The accompanying drawings which are made a part of the specification, illustrate the invention and will be referred to throughout the following description, similar reference characters being employed to designate corresponding parts.

In the said drawings Figure 1 is a front elevation of a cabinet embodying the improvement.

Fig. 2 is a side elevation partially in vertical section, substantially on line 2—2, Fig. 1.

Fig. 3 is a front elevation showing a difference in top design, and a certain adjustment of one of the novel features that will be hereinafter set forth.

Fig. 4 is a horizontal section on line 4—4 of Fig. 2.

Fig. 5 is a top view of the door, detached, and Fig. 6 is an inside view of said door.

Fig. 7 is a horizontal section on line 7—7 of Fig. 3, and Fig. 8 is a section on line 8—8 of Fig. 7.

In the embodiment as illustrated, a lower compartment 1 is provided for the storage of records, an upper compartment 2 for the sound producing elements of the phonograph, and an intermediate section 3 which contains the operating mechanism and horn of the instrument. This general arrangement is similar to that of ordinary construction of cabinets of this class, with the exception of the top member.

The top 4 of the improved cabinet is stationary and therefore may be utilized as a stand for ornaments or serviceable articles as, for example, a clock 5 as shown in Figs. 1 and 2, or for a curio case 6, shown in Fig. 3.

The front of compartment 2 is provided with an opening 7, adapted to be covered and uncovered on the interior by a door member 8 of novel construction and operation, which will now be described.

Two pairs of brackets 9 and 10 are attached to the interior face of the door 8 near the lateral edges thereof, substantially in the location shown, the brackets 9 being above the brackets 10 and in a different vertical plane. Rollers 11 and 12 are mounted on the brackets 9 and 10 respectively. These rollers extend beyond the lateral edges of the door and enter grooves 13 and 14, said grooves being on the interior of the lateral walls of the compartment 2. The grooves may be cut in the sides 1^a and 1^b, but for convenience of assembling and other obvious reasons, they are preferably formed in auxiliary members 15 and 16, see Fig. 4, the said members 15 and 16 being attached to the walls 1^a and 1^b respectively. The groove 13 in member 15 corresponds to a like groove in member 16, and groove 14 of member 15 corresponds to a groove in member 16.

The door 8 is provided with a knob or handle member 17 on the exterior thereof, and a like member 18 is attached to the interior of said door.

It will readily be seen by reference to Fig. 2 that the operator can grasp the handle 17 and raise the door to the position shown by dotted lines, Fig. 2, and thus un-

cover the opening 7. In this operation the rollers 12 travel in the grooves 14, and the rollers 11 travel in the segmental grooves 13. The upper terminals 13 and 14 are off-set or 5 extended horizontally as shown at 13^a and 14^a thereby providing means for retaining the door in a horizontal elevated position. The door is closed by manipulating the interior handle 18. This construction provides 10 access to the compartment 2 without disturbing the top member of the cabinet.

In the operation of phonographs for amusement purposes, the operator or his audience may be in doubt as to what record 15 is wanted to replace one that has been played, or a quick change of records may be desirable. For the above mentioned, and other apparent reasons, an intermediate record receptacle or support is a desirable 20 feature of a cabinet of this character. With this end in view, I provide a structure adapted to operate in a section of the intermediate compartment 3. The front member 19 of said structure registers with an 25 opening in the front wall of the cabinet, and extends more or less as desired, into the compartment. The member 19 is provided with a stem 20, which is adapted to slide horizontally and to oscillate in bearings 21 and 22. A segmental stop member 23 is attached to the stem 20 and co-acts with a buttress member 24 to limit the oscillation of 30 the stem to 90°. The member 19 is provided with one or more record holders, which may 35 be in the form of segmental slots 25.

When it is desired to make a change of records, the member 19 is pulled forward by means of the knob 26, until it clears the face of the cabinet body, or until a stop 20^a 40 attached to the stem 20, strikes the bearing partition 21. The member 19 can then be oscillated 90° or to the position shown in Fig. 3, thus providing a temporary receptacle for one or more records.

45 The convenience provided by this construction is obvious. One or more records may be removed from the storage compartment 1 and deposited in the rack 19, the record that is on the instrument can be dislodged therefrom and exchanged for one of the records in the rack, the said rack providing a repository for the dislodged record during the transferring process. The records can be transferred from the rack 50 19 to the storage compartment 1, and the rack returned to its normal position lea-

surely, without annoyance to the operator or the audience.

A device adapted for storage of phonograph needles is provided in the compartment 3, said device comprising a door 27 having one or more cups 28 mounted thereon and adapted to swing outward on hinges 29, a knob 30 being attached to said door for manipulating same. 60

The improved cabinet may be more or less ornamental, and the details of construction and arrangement of elements may be changed without departure from the nature of the invention, the limitations of modifications being governed by the scope of the appended claims. 70

What I claim and desire to secure by Letters Patent is.

1. A phonograph cabinet including an instrument compartment, an oscillating temporary record support below the instrument compartment, and a record storage compartment below said temporary support, the instrument compartment being provided with 75 a door in the front wall thereof, a pair of trunnions mounted on said door in juxtaposition to the lateral edges thereof and in the same transverse plane, vertical grooves in the side walls of the compartment, in 80 which said trunnions travel, a second pair of trunnions mounted on the door in a transverse plane back of the first named trunnions, and segmental grooves in the side walls of the compartment, in which the last 85 named trunnions travel. 90

2. A phonograph cabinet including an instrument compartment, an oscillating temporary record support below the instrument compartment, and a record storage compartment below said temporary support, the instrument compartment being provided with a door in the front wall thereof, a pair of trunnions mounted on said door in juxtaposition to the lateral edges thereof and in 95 the same transverse plane, vertical grooves in the side walls of the compartment, in which said trunnions travel, a second pair of trunnions mounted on the door in a transverse plane back of the first named trunnions, segmental grooves in the side walls of the compartment, in which the last named trunnions travel, and means for governing 100 the oscillation of the temporary record support. 105

In testimony whereof I affix my signature.
WESLEY H. BENNINGTON. 110
